[57]

ABSTRACT

A paper feed system for an accounting machine or the like which includes a main platen and an independent platen over which continuous forms are fed by a line feed mechanism and journal sheets are fed by a form feed mechanism. The line feed and form feed mechanisms are selectively driven from a common shaft through corresponding clutch mechanisms. The common shaft is selectively driven from a continuously rotating motor shaft through a selectively actuated clutch. The engagement of the clutches is controlled by a programmed operating device.

PAPER FEED SYSTEM FOR ACCOUNTING MACHINES

CROSS REFERENCE TO RELATED APPLICATION

Applicants claim priority from corresponding Italian patent application Ser. No. 50170-A68, filed Jan. 18, 1968.

BACKGROUND OF THE INVENTION

1. Field of the Invention

The present invention relates to a paper feed system for an accounting or other such office machine having a platen and a device for rotating the platen to advance a journal sheet or other document which is guided round the platen and also a device for advancing continuous forms independently of the journal sheet or other document.

2. Description of the Prior Art

Various paper feed systems of the type described are known. In these systems, the advance of the journal sheet and the continuous forms is effected by independent means controlled independently of the program of the machine, as a result of which the systems are very complicated and costly and require special devices for synchronizing the operation of the independent means.

SUMMARY OF THE INVENTION

With a view to obviating such drawbacks, the present invention provides a paper feed system for an accounting or other such office machine, comprising a platen, means for guiding a sheet of paper around the platen, at least one guide mechanism for continuous forms, a first device adapted to be actuated to rotate the platen and carry the paper sheet along, a second device adapted to be actuated to carry the continuous forms along independently of the journal sheet, a continuously rotating driving shaft, intermediate means adapted to be actuated by the driving shaft through the medium of an actuating clutch, a first presetting clutch between the said intermediate means and the said first device and a second presetting clutch between the said intermediate means and the said second device, and programmed operating means adapted to command the engagement of the actuating clutch and of at least one of the presetting clutches.

BRIEF DESCRIPTION OF THE DRAWING

FIG. 1 is a partial plan view of an accounting machine incorporating a paper feed system according to the invention;

FIG. 2 is the first part of a section, on a larger scale, on section line II-II of FIG. 1;

FIG. 3 is the second part of the larger-scale section on section line II-II of FIG. 1;

FIG. 4 is a diagram showing FIGS. 2 and 3 put together;

FIG. 5 is a plan view of a detail of the feed system;

FIG. 6 is a front perspective view of a detail of the system from the left;

FIG. 7 is a rear perspective view of another detail of the system from the left;

FIG. 8 is a rear perspective view of another detail of the system from the left;

FIG. 9 is a rear perspective view of another detail of the system from the left;

FIG. 10 is a perspective view of another detail of the system from the left;

FIG. 11 is a diagram showing the working principle of the feed system.

DETAILED DESCRIPTION OF THE INVENTION

General Description

The paper feed system is incorporated in an accounting machine (FIG. 1) comprising a fixed frame formed by two side walls 20 connected by a series of angle irons extending across the machine. The machine moreover comprises two coaxial shafts 21 and 22 rotatable in the side walls 20 of the frame of the machine and on which there are respectively fixed a main platen 23 and an auxiliary platen 24.

The two shafts 21 and 22 are interconnected in such a manner as to be capable of being rotated independently auxiliary as described in copending application Ser. No. 774,375 filed Nov. 8, 1968 in the name of A. Cortona et al. and assigned to the same assignee as this application, for which reason the auxiliary platen 24 will be referred to hereinafter as the independent platen. The shafts 21 and 22 carry two knobs 26 and 27 at the opposite ends for manual operation of the platens 23 and 24 as described in copending application Ser. No. 774,375 filed Nov. 8, 1968 as described in copending application Ser. No. 774,375 Nov. 8, 1968 in the name of A. Cortona et al., and assigned to the same assignee as this application.

Behind platens 23 and 24, spindle 28 is mounted in side walls 20 and supports at least one roll of paper 29 (FIG. 3) over which is wrapped a journal sheet 31, which generally concerns only main platen 23. However, two separate rolls of paper 29 for two separate journal sheets 31, one for each platen 23 and 24, may be mounted side by side on spindle 28. Each journal sheet 31 is guided for a certain distance by two lateral guide plates 32 mounted slidably on bar 33 fixed to side walls 20 of the machine. A support plate 34 (FIG. 2) extending over the entire width of the machine is adapted to support journal sheet 31 in the section between lateral plates 32 and main platen 23 and independent platen 24. As shown in FIG. 2 above main platen 23 and independent platen 24 there is disposed a series of bail rollers 36. Another series of bail rollers 37 is disposed to the rear of platens 23 and 24. A device 30 for raising and lowering bail rollers 36 and 37 comprises a manually operated lever 38 fixed to spindle 39 rotatable in the two side walls 20. Keyed on spindle 39 is a cam 41 against which there normally bears pin 42 on lever 43 pivoted on a fixed spindle 44 and biased to turn clockwise by spring 46. The lever 43 is connected by rod 47 and rod 48 to a second lever, not shown in the drawing, but which parallels lever 43 at the other side of the machine in such manner as to form a rigid frame. The rod 47 co-operates with a series of lugs 49 integral with corresponding arms 51. The arms 51 can turn on spindle 44 and are connected in pairs by short spindles 52 on which rollers 37 are rotatable, the rollers 37 being normally held so that they bear against platens 23 and 24 by means of a series of springs 53 connecting arms 51 to rod 48.

Keyed on spindle 39 is a plate 54 having a cam slot 56 in which is engaged pin 57 on crank 58 fixed on shaft 59 rotatable in the frame of the machine. Also fixed on shaft 59 are two plates 61, only one of which can be seen in FIG. 2. The two plates 61 are connected by rod 62 and support rule 63 having serrated edge 64 for enabling journal sheet 31 to be cut. On the rod 62 there is pivoted a series of arms 66 connected in pairs by short spindles 67 on which rollers 36 are rotatable. Each arm 66 is connected to rule 63 at its rear end by spring 68.

55 The accounting machine moreover comprises (FIG. 1) a feed arrangement for two continuous forms 69 and 71 of the type having a series of holes 72 on each side. More particularly, shaft 73 rotatable in the side walls 20 is provided with an operating knob 74 and carries two pin wheels 76 each angularly fast with shaft 73. Two plates 77 fixed to fixed T-section 78 are respectively associated with the two pin wheels 76 and are adapted to support and guide continuous form 69 which is fed off the platen 23 via wheels 76.

Another shaft 81 rotatable in side walls 20 is provided with 65 an operating knob 82 and carries two pin wheels 83 each angularly fast with shaft 81. Two plates 84 are fixed to a second fixed T-section bar 86 and, similarly to plates 77, are respectively associated with the two pin wheels 83 and are adapted to support and guide continuous form 71 which is fed off the platen 24 via wheels 83.

At the back of the machine there is fixed a spindle 93 above and below which are fixed two hollow bar members 94 with rounded edges. Clamps 400 (FIG. 3) can be fixed on spindle 93 in suitable transverse positions, each of these clamps 400 75 being formed by a pair of arms 96 held bearing against bar

members 94 by compression spring 97. The two continuous forms 69 71 are fed in between bar members 94 respectively and the corresponding arms 96 of the clamps. The forms 69 and 71 are moreover supported and guided towards platens 23 and 24 by plate 98 secured to the side walls 20.

The form 69 can be drawn off by pin wheels 76 and form 71 can be drawn off by pin wheels 83.

Mounted in the front parts of side walls 20, below platens 23 and 24, is a series of front paper-pressing rollers 101 (FIG. 2) adapted to hold continuous forms 69 and 71 in contact with platens 23 and 24. The opening and closing of front rollers 101 is effected by eccentric 102 keyed on shaft 103 adapted to be rotated through 180° in a manner conventionally known under the control of the program-equipped operating device 145 (FIG. 11) or as a result of manual operation. A connecting rod 104 (FIG. 2) co-operates with eccentric 102 and is connected in turn to crank 106 keyed on shaft 107 rotatable in the two side walls 20 of the machine.

Pairs of levers 108 connected by small rods 109 are keyed on shaft 107 (FIG. 1). Connected to rods 109 (FIG. 2) by means of springs 111 are pairs of levers 112 pivoted on shaft 107 and connected by short spindles 113 on which rollers 101 are rotatable. In correspondence with each pair of levers 112 there is disposed a plate 114 connected to rod 109 by means of a spring 115 and provided with two lateral guide tongues 116 co-operating with lever 112. Each plate 114 is moreover provided with a pin 117, by means of which it bears on shaft 107, and with two lugs 118 connected to the two levers 112 by a pin 401 and slot 402.

On the front parts of side walls 20 there are fixed two guides 120 and 121 on which carriage 124 bearing a group of type wheels 126 is slidably by means of rollers 122 and 123, respectively. The carriage 124 can be shifted transversely step by step or in tabulating jumps to bring wheels 126 to write in the various transverse positions of journal sheet 31 and of the continuous forms 69 and 71 in known manner.

To insert a journal sheet 31 and the continuous forms 69 and 71 (FIG. 2) over the platens 23 and 24, it is necessary to open rollers 36, 37 and 101. Normally, at the end of an accounting operation, the program of the machine (FIG. 1) causes shaft 103 to rotate through 180° with respect to the position shown in FIG. 2. The eccentric 102 rotates with shaft 103 and causes connecting rod 104 to shift to the left. The connecting rod 104 causes crank 106, shaft 107 and levers 108 to rotate clockwise. The springs 111 and 115 are then relaxed and allow levers 112 and plates 114 to turn clockwise through their own weight, as a result of which rollers 101 move away from platens 23 and 24.

To open top rollers 36 and rear rollers 37, lever 38 is depressed, causing spindle 39, cam 41 and plate 54 to rotate anticlockwise. By means of slot 56 and pin 57, plate 54 causes crank 58 and shaft 59 to rotate anticlockwise. Consequently, plates 61 also rotate anticlockwise together with shaft 59 and move rollers 36 away from platens 23 and 24. The cam 41, in turn, allows lever 43 to turn clockwise by the action of spring 46. The rod 47 acts on the abutments 49 of arms 51 and causes the latter to turn clockwise together with rollers 37, which therefore move away from platens 23 and 24.

The journal sheet 31 is now introduced first by unrolling it from roll 29 (FIG. 3). The journal sheet 31 passes forward between the lateral guide plates 32 and over support plate 34 (FIG. 2), is inserted between rollers 37 and 101 and platen 23 and passed round the latter, passes below rollers 36, slides in the rearward direction over plate 34 and between the lateral plates 32 and, passing above roll 29, arrives behind the machine, where it is collected in a hopper, which is not shown in the drawing. After the journal sheet 31 has been introduced, rollers 36 and 37 can be closed by raising manual operating lever 38.

The perforated continuous forms 69 and 71, which are normally folded in zig-zag form in containers not shown in the drawing and arranged at the back of the accounting machine, are then introduced. The forms 69 and 71 are inserted

between bar members 94 and the corresponding arms 96 of the clamps 400 fixed on spindle 93 and are made to slide over guide plate 98. The forms 69 and 71 then pass between rollers 101 and platens 23 and 24.

5 The form 69 is finally carried over pin wheels 76 (FIGS. 1 and 2) and the lateral perforations 72 are engaged with the pins of wheels 76, the form 69 resting on plates 77. Similarly, form 71 is brought into engagement with pin wheels 83 and rests on plates 84. The forms 69 and 71 are then collected in the hoppers of known type not shown in the drawing which are arranged at the back of the machine.

FEED OF THE JOURNAL SHEET

15 The main platen 23 and the independent platen 24 can be rotated independently of one another by two separate line-spacing control arrangements. The line-spacing control arrangement of main platen 23 is contained in a housing comprising two side walls 130 and 131 (FIG. 5) connected by three spaced plates 132, 133 and 134. A dividing wall 136 is connected between plates 133 and 134. The side walls 130 and 131 can be mounted easily on the fixed frame of the machine at four points 137.

20 The line-spacing control arrangement for platen 23 comprises a presetting electromagnet 138 (FIG. 11) which is normally deenergized and adapted to be energized by a programmed operating device indicated generally by the reference numeral 145 and comprising, for example, a magnetic tape on which the program information is recorded. The electromagnet 138 (FIG. 6) is provided with an armature 139 pivoting on a fixed spindle 140 and connected by a pin 403 and slot 404 to a slider 141 drawn to the right (in FIG. 6) by a spring 142. The slider 141 is provided with a slot 143 in engagement with shaft 144 adapted to be shifted cyclically along a closed path by means of a kinematic chain of the type shown in FIG. 7 and described in copending application Ser. No. 773,872 filed Nov. 6, 1968 in the name of A. Cortona et al. and assigned to the same assignee as this application, now abandoned.

25 The kinematic chain is actuated by a main shaft 146 (FIG. 7) adapted to be rotated clockwise cyclically by clutch 147. The shaft 146 (FIG. 5) has keyed to it a helical gear 262 which is fast with the driving part of the clutch 147 and meshes with a helical gear 263 fixed on a shaft 264 rotatable in the walls 131, 136. The shaft 264 is connected by means of a pair of helical gears 266, 267 to a shaft 268 rotatable in the walls 133, 134. Fixed to the shaft 268 is a helical gear 269 meshing with a helical gear 271 fixed to a main driving shaft 239 rotated continuously by an electric motor not shown in the drawing.

30 The clutch 147 (FIG. 7) is normally held open or disengaged by an arm 150 of a bail 148 pivoted on a fixed spindle 149 and adapted to cooperate with a tooth 151 of clutch 147. 35 The bail 148 is provided with an arm 152 adapted to cooperate with cam 153 on shaft 146. The bail 148 moreover has a lug 154 which is normally held by spring 160 so that it bears against lever 155 pivoted on fixed spindle 156 and connected by means of a pin 405 and slot 406 and spring 165 to slider 170 corresponding to the slider 41 of patent application Ser. No. 773,872 to which reference has been made. The slider 170 is normally held in the position shown in FIG. 7 by a start electromagnet 157 (FIG. 11) which is normally energized and is driven by device 145.

40 The slider 141 (FIG. 6) is moreover provided with lug 158 adapted to cooperate alternately with the ends of two push rods 159 and 161. The push rods 159 and 161 are normally guided vertically by a fixed spindle 162 and are pivoted to two opposite arms of a rocking lever 163 pivoting on fixed spindle 164. The rocking lever 163 is in engagement with slider 166 slidable horizontally on fixed spindle 167 and connected by means of lever 168 to slider 169. The latter is provided with pin 171 inserted in notch 172 in rocking lever 173 pivoted on fixed spindle 175.

45 The slider 141 (FIG. 6) is connected by a pin 173 and slot 174 to a lever 175 pivoted on a fixed spindle 176 and connected by a pin 177 and slot 178 to a lever 179 pivoted on a fixed spindle 180. The lever 179 is connected by a pin 181 and slot 182 to a lever 183 pivoted on a fixed spindle 184 and connected by a pin 185 and slot 186 to a lever 187 pivoted on a fixed spindle 188. The lever 187 is connected by a pin 189 and slot 190 to a lever 191 pivoted on a fixed spindle 192 and connected by a pin 193 and slot 194 to a lever 195 pivoted on a fixed spindle 196. The lever 195 is connected by a pin 197 and slot 198 to a lever 199 pivoted on a fixed spindle 200 and connected by a pin 201 and slot 202 to a lever 203 pivoted on a fixed spindle 204. The lever 203 is connected by a pin 205 and slot 206 to a lever 207 pivoted on a fixed spindle 208 and connected by a pin 209 and slot 210 to a lever 211 pivoted on a fixed spindle 212. The lever 211 is connected by a pin 213 and slot 214 to a lever 215 pivoted on a fixed spindle 216 and connected by a pin 217 and slot 218 to a lever 219 pivoted on a fixed spindle 220. The lever 219 is connected by a pin 221 and slot 222 to a lever 223 pivoted on a fixed spindle 224 and connected by a pin 225 and slot 226 to a lever 227 pivoted on a fixed spindle 228. The lever 227 is connected by a pin 229 and slot 230 to a lever 231 pivoted on a fixed spindle 232 and connected by a pin 233 and slot 234 to a lever 235 pivoted on a fixed spindle 236. The lever 235 is connected by a pin 237 and slot 238 to a lever 239 pivoted on a fixed spindle 240 and connected by a pin 241 and slot 242 to a lever 243 pivoted on a fixed spindle 244. The lever 243 is connected by a pin 245 and slot 246 to a lever 247 pivoted on a fixed spindle 248 and connected by a pin 249 and slot 250 to a lever 251 pivoted on a fixed spindle 252. The lever 251 is connected by a pin 253 and slot 254 to a lever 255 pivoted on a fixed spindle 256 and connected by a pin 257 and slot 258 to a lever 259 pivoted on a fixed spindle 260. The lever 259 is connected by a pin 261 and slot 262 to a lever 263 pivoted on a fixed spindle 264 and connected by a pin 265 and slot 266 to a lever 267 pivoted on a fixed spindle 268. The lever 267 is connected by a pin 269 and slot 270 to a lever 271 pivoted on a fixed spindle 273 and connected by a pin 275 and slot 276 to a lever 277 pivoted on a fixed spindle 279. The lever 277 is connected by a pin 281 and slot 282 to a lever 283 pivoted on a fixed spindle 285 and connected by a pin 287 and slot 288 to a lever 289 pivoted on a fixed spindle 291. The lever 289 is connected by a pin 293 and slot 294 to a lever 295 pivoted on a fixed spindle 297 and connected by a pin 299 and slot 300 to a lever 301 pivoted on a fixed spindle 303. The lever 301 is connected by a pin 305 and slot 306 to a lever 307 pivoted on a fixed spindle 309 and connected by a pin 311 and slot 312 to a lever 313 pivoted on a fixed spindle 315. The lever 313 is connected by a pin 317 and slot 318 to a lever 319 pivoted on a fixed spindle 321 and connected by a pin 325 and slot 326 to a lever 327 pivoted on a fixed spindle 329. The lever 327 is connected by a pin 331 and slot 332 to a lever 333 pivoted on a fixed spindle 335 and connected by a pin 339 and slot 340 to a lever 341 pivoted on a fixed spindle 343. The lever 341 is connected by a pin 345 and slot 346 to a lever 347 pivoted on a fixed spindle 349 and connected by a pin 353 and slot 354 to a lever 355 pivoted on a fixed spindle 357. The lever 355 is connected by a pin 361 and slot 362 to a lever 363 pivoted on a fixed spindle 365 and connected by a pin 369 and slot 370 to a lever 371 pivoted on a fixed spindle 373. The lever 371 is connected by a pin 377 and slot 378 to a lever 379 pivoted on a fixed spindle 381 and connected by a pin 385 and slot 386 to a lever 387 pivoted on a fixed spindle 389. The lever 387 is connected by a pin 393 and slot 394 to a lever 395 pivoted on a fixed spindle 397 and connected by a pin 401 and slot 402 to a lever 403 pivoted on a fixed spindle 405. The lever 403 is connected by a pin 409 and slot 410 to a lever 411 pivoted on a fixed spindle 413 and connected by a pin 417 and slot 418 to a lever 419 pivoted on a fixed spindle 421. The lever 419 is connected by a pin 425 and slot 426 to a lever 427 pivoted on a fixed spindle 429 and connected by a pin 433 and slot 434 to a lever 435 pivoted on a fixed spindle 437. The lever 435 is connected by a pin 441 and slot 442 to a lever 443 pivoted on a fixed spindle 445 and connected by a pin 451 and slot 452 to a lever 453 pivoted on a fixed spindle 455. The lever 453 is connected by a pin 459 and slot 460 to a lever 461 pivoted on a fixed spindle 463 and connected by a pin 469 and slot 470 to a lever 471 pivoted on a fixed spindle 473. The lever 471 is connected by a pin 477 and slot 478 to a lever 479 pivoted on a fixed spindle 481 and connected by a pin 485 and slot 486 to a lever 487 pivoted on a fixed spindle 489. The lever 487 is connected by a pin 493 and slot 494 to a lever 495 pivoted on a fixed spindle 497 and connected by a pin 501 and slot 502 to a lever 503 pivoted on a fixed spindle 505. The lever 503 is connected by a pin 509 and slot 510 to a lever 511 pivoted on a fixed spindle 513 and connected by a pin 517 and slot 518 to a lever 519 pivoted on a fixed spindle 521. The lever 519 is connected by a pin 525 and slot 526 to a lever 527 pivoted on a fixed spindle 529 and connected by a pin 535 and slot 536 to a lever 537 pivoted on a fixed spindle 539. The lever 537 is connected by a pin 545 and slot 546 to a lever 547 pivoted on a fixed spindle 549 and connected by a pin 553 and slot 554 to a lever 555 pivoted on a fixed spindle 557. The lever 555 is connected by a pin 561 and slot 562 to a lever 563 pivoted on a fixed spindle 565 and connected by a pin 569 and slot 570 to a lever 571 pivoted on a fixed spindle 573. The lever 571 is connected by a pin 577 and slot 578 to a lever 579 pivoted on a fixed spindle 581 and connected by a pin 585 and slot 586 to a lever 587 pivoted on a fixed spindle 589. The lever 587 is connected by a pin 593 and slot 594 to a lever 595 pivoted on a fixed spindle 597 and connected by a pin 601 and slot 602 to a lever 603 pivoted on a fixed spindle 605. The lever 603 is connected by a pin 609 and slot 610 to a lever 611 pivoted on a fixed spindle 613 and connected by a pin 617 and slot 618 to a lever 619 pivoted on a fixed spindle 621. The lever 619 is connected by a pin 625 and slot 626 to a lever 627 pivoted on a fixed spindle 629 and connected by a pin 635 and slot 636 to a lever 637 pivoted on a fixed spindle 639. The lever 637 is connected by a pin 645 and slot 646 to a lever 647 pivoted on a fixed spindle 649 and connected by a pin 653 and slot 654 to a lever 655 pivoted on a fixed spindle 657. The lever 655 is connected by a pin 661 and slot 662 to a lever 663 pivoted on a fixed spindle 665 and connected by a pin 669 and slot 670 to a lever 671 pivoted on a fixed spindle 673. The lever 671 is connected by a pin 677 and slot 678 to a lever 679 pivoted on a fixed spindle 681 and connected by a pin 685 and slot 686 to a lever 687 pivoted on a fixed spindle 689. The lever 687 is connected by a pin 693 and slot 694 to a lever 695 pivoted on a fixed spindle 697 and connected by a pin 701 and slot 702 to a lever 703 pivoted on a fixed spindle 705. The lever 703 is connected by a pin 709 and slot 710 to a lever 711 pivoted on a fixed spindle 713 and connected by a pin 717 and slot 718 to a lever 719 pivoted on a fixed spindle 721. The lever 719 is connected by a pin 725 and slot 726 to a lever 727 pivoted on a fixed spindle 729 and connected by a pin 735 and slot 736 to a lever 737 pivoted on a fixed spindle 739. The lever 737 is connected by a pin 745 and slot 746 to a lever 747 pivoted on a fixed spindle 749 and connected by a pin 753 and slot 754 to a lever 755 pivoted on a fixed spindle 757. The lever 755 is connected by a pin 761 and slot 762 to a lever 763 pivoted on a fixed spindle 765 and connected by a pin 769 and slot 770 to a lever 771 pivoted on a fixed spindle 773. The lever 771 is connected by a pin 777 and slot 778 to a lever 779 pivoted on a fixed spindle 781 and connected by a pin 785 and slot 786 to a lever 787 pivoted on a fixed spindle 789. The lever 787 is connected by a pin 793 and slot 794 to a lever 795 pivoted on a fixed spindle 797 and connected by a pin 801 and slot 802 to a lever 803 pivoted on a fixed spindle 805. The lever 803 is connected by a pin 809 and slot 810 to a lever 811 pivoted on a fixed spindle 813 and connected by a pin 817 and slot 818 to a lever 819 pivoted on a fixed spindle 821. The lever 819 is connected by a pin 825 and slot 826 to a lever 827 pivoted on a fixed spindle 829 and connected by a pin 835 and slot 836 to a lever 837 pivoted on a fixed spindle 839. The lever 837 is connected by a pin 845 and slot 846 to a lever 847 pivoted on a fixed spindle 849 and connected by a pin 853 and slot 854 to a lever 855 pivoted on a fixed spindle 857. The lever 855 is connected by a pin 861 and slot 862 to a lever 863 pivoted on a fixed spindle 865 and connected by a pin 869 and slot 870 to a lever 871 pivoted on a fixed spindle 873. The lever 871 is connected by a pin 877 and slot 878 to a lever 879 pivoted on a fixed spindle 881 and connected by a pin 885 and slot 886 to a lever 887 pivoted on a fixed spindle 889. The lever 887 is connected by a pin 893 and slot 894 to a lever 895 pivoted on a fixed spindle 897 and connected by a pin 901 and slot 902 to a lever 903 pivoted on a fixed spindle 905. The lever 903 is connected by a pin 909 and slot 910 to a lever 911 pivoted on a fixed spindle 913 and connected by a pin 917 and slot 918 to a lever 919 pivoted on a fixed spindle 921. The lever 919 is connected by a pin 925 and slot 926 to a lever 927 pivoted on a fixed spindle 929 and connected by a pin 935 and slot 936 to a lever 937 pivoted on a fixed spindle 939. The lever 937 is connected by a pin 945 and slot 946 to a lever 947 pivoted on a fixed spindle 949 and connected by a pin 953 and slot 954 to a lever 955 pivoted on a fixed spindle 957. The lever 955 is connected by a pin 961 and slot 962 to a lever 963 pivoted on a fixed spindle 965 and connected by a pin 969 and slot 970 to a lever 971 pivoted on a fixed spindle 973. The lever 971 is connected by a pin 977 and slot 978 to a lever 979 pivoted on a fixed spindle 981 and connected by a pin 985 and slot 986 to a lever 987 pivoted on a fixed spindle 989. The lever 987 is connected by a pin 993 and slot 994 to a lever 995 pivoted on a fixed spindle 997 and connected by a pin 1001 and slot 1002 to a lever 1003 pivoted on a fixed spindle 1005. The lever 1003 is connected by a pin 1009 and slot 1010 to a lever 1011 pivoted on a fixed spindle 1013 and connected by a pin 1017 and slot 1018 to a lever 1019 pivoted on a fixed spindle 1021. The lever 1019 is connected by a pin 1025 and slot 1026 to a lever 1027 pivoted on a fixed spindle 1029 and connected by a pin 1035 and slot 1036 to a lever 1037 pivoted on a fixed spindle 1039. The lever 1037 is connected by a pin 1045 and slot 1046 to a lever 1047 pivoted on a fixed spindle 1049 and connected by a pin 1053 and slot 1054 to a lever 1055 pivoted on a fixed spindle 1057. The lever 1055 is connected by a pin 1061 and slot 1062 to a lever 1063 pivoted on a fixed spindle 1065 and connected by a pin 1069 and slot 1070 to a lever 1071 pivoted on a fixed spindle 1073. The lever 1071 is connected by a pin 1077 and slot 1078 to a lever 1079 pivoted on a fixed spindle 1081 and connected by a pin 1085 and slot 1086 to a lever 1087 pivoted on a fixed spindle 1089. The lever 1087 is connected by a pin 1093 and slot 1094 to a lever 1095 pivoted on a fixed spindle 1097 and connected by a pin 1101 and slot 1102 to a lever 1103 pivoted on a fixed spindle 1105. The lever 1103 is connected by a pin 1109 and slot 1110 to a lever 1111 pivoted on a fixed spindle 1113 and connected by a pin 1117 and slot 1118 to a lever 1119 pivoted on a fixed spindle 1121. The lever 1119 is connected by a pin 1125 and slot 1126 to a lever 1127 pivoted on a fixed spindle 1129 and connected by a pin 1135 and slot 1136 to a lever 1137 pivoted on a fixed spindle 1139. The lever 1137 is connected by a pin 1145 and slot 1146 to a lever 1147 pivoted on a fixed spindle 1149 and connected by a pin 1153 and slot 1154 to a lever 1155 pivoted on a fixed spindle 1157. The lever 1155 is connected by a pin 1161 and slot 1162 to a lever 1163 pivoted on a fixed spindle 1165 and connected by a pin 1169 and slot 1170 to a lever 1171 pivoted on a fixed spindle 1173. The lever 1171 is connected by a pin 1177 and slot 1178 to a lever 1179 pivoted on a fixed spindle 1181 and connected by a pin 1185 and slot 1186 to a lever 1187 pivoted on a fixed spindle 1189. The lever 1187 is connected by a pin 1193 and slot 1194 to a lever 1195 pivoted on a fixed spindle 1197 and connected by a pin 1201 and slot 1202 to a lever 1203 pivoted on a fixed spindle 1205. The lever 1203 is connected by a pin 1209 and slot 1210 to a lever 1211 pivoted on a fixed spindle 1213 and connected by a pin 1217 and slot 1218 to a lever 1219 pivoted on a fixed spindle 1221. The lever 1219 is connected by a pin 1225 and slot 1226 to a lever 1227 pivoted on a fixed spindle 1229 and connected by a pin 1235 and slot 1236 to a lever 1237 pivoted on a fixed spindle 1239. The lever 1237 is connected by a pin 1245 and slot 1246 to a lever 1247 pivoted on a fixed spindle 1249 and connected by a pin 1253 and slot 1254 to a lever 1255 pivoted on a fixed spindle 1257. The lever 1255 is connected by a pin 1261 and slot 1262 to a lever 1263 pivoted on a fixed spindle 1265 and connected by a pin 1269 and slot 1270 to a lever 1271 pivoted on a fixed spindle 1273. The lever 1271 is connected by a pin 1277 and slot 1278 to a lever 1279 pivoted on a fixed spindle 1281 and connected by a pin 1285 and slot 1286 to a lever 1287 pivoted on a fixed spindle 1289. The lever 1287 is connected by a pin 1293 and slot 1294 to a lever 1295 pivoted on a fixed spindle 1297 and connected by a pin 1301 and slot 1302 to a lever 1303 pivoted on a fixed spindle 1305. The lever 1303 is connected by a pin 1309 and slot 1310 to a lever 1311 pivoted on a fixed spindle 1313 and connected by a pin 1317 and slot 1318 to a lever 1319 pivoted on a fixed spindle 1321. The lever 1319 is connected by a pin 1325 and slot 1326 to a lever 1327 pivoted on a fixed spindle 1329 and connected by a pin 1335 and slot 1336 to a lever 1337 pivoted on a fixed spindle 1339. The lever 1337 is connected by a pin 1345 and slot 1346 to a lever 1347 pivoted on a fixed spindle 1349 and connected by a pin 1353 and slot 1354 to a lever 1355 pivoted on a fixed spindle 1357. The lever 1355 is connected by a pin 1361 and slot 1362 to a lever 1363 pivoted on a fixed spindle 1365 and connected by a pin 1369 and slot 1370 to a lever 1371 pivoted on a fixed spindle 1373. The lever 1371 is connected by a pin 1377 and slot 1378 to a lever 1379 pivoted on a fixed spindle 1381 and connected by a pin 1385 and slot 1386 to a lever 1387 pivoted on a fixed spindle 1389. The lever 1387 is connected by a pin 1393 and slot 1394 to a lever 1395 pivoted on a fixed spindle 1397 and connected by a pin 1401 and slot 1402 to a lever 1403 pivoted on a fixed spindle 1405. The lever 1403 is connected by a pin 1409 and slot 1410 to a lever 1411 pivoted on a fixed spindle 1413 and connected by a pin 1417 and slot 1418 to a lever 1419 pivoted on a fixed spindle 1421. The lever 1419 is connected by a pin 1425 and slot 1426 to a lever 1427 pivoted on a fixed spindle 1429 and connected by a pin 1435 and slot 1436 to a lever 1437 pivoted on a fixed spindle 1439. The lever 1437 is connected by a pin 1445 and slot 1446 to a lever 1447 pivoted on a fixed spindle 1449 and connected by a pin 1453 and slot 1454 to a lever 1455 pivoted on a fixed spindle 1457. The lever 1455 is connected by a pin 1461 and slot 1462 to a lever 1463 pivoted on a fixed spindle 1465 and connected by a pin 1469 and slot 1470 to a lever 1471 pivoted on a fixed spindle 1473. The lever 1471 is connected by a pin 1477 and slot 1478 to a lever 1479 pivoted on a fixed spindle 1481 and connected by a pin 1485 and slot 1486 to a lever 1487 pivoted on a fixed spindle 1489. The lever 1487 is connected by a pin 1493 and slot 1494 to a lever 1495 pivoted on a fixed spindle 1497 and connected by a pin 1501 and slot 1502 to a lever 1503 pivoted on a fixed spindle 1505. The lever 1503 is connected by a pin 1509 and slot 1510 to a lever 1511 pivoted on a fixed spindle 1513 and connected by a pin 1517 and slot 1518 to a lever 1519 pivoted on a fixed spindle 1521. The lever 1519 is connected by a pin 1525 and slot 1526 to a lever 1527 pivoted on a fixed spindle 1529 and connected by a pin 1535 and slot 1536 to a lever 1537 pivoted on a fixed spindle 1539. The lever 1537 is connected by a pin 1545 and slot 1546 to a lever 1547 pivoted on a fixed spindle 1549 and connected by a pin 1553 and slot 1554 to a lever 1555 pivoted on a fixed spindle 1557. The lever 1555 is connected by a pin 1561 and slot 1562 to a lever 1563 pivoted on a fixed spindle 1565 and connected by a pin 1569 and slot 1570 to a lever 1571 pivoted on a fixed spindle 1573. The lever 1571 is connected by a pin 1577 and slot 1578 to a lever 1579 pivoted on a fixed spindle 1581 and connected by a pin 1585 and slot 1586 to a lever 1587 pivoted on a fixed spindle 1589. The lever 1587 is connected by a pin 1593 and slot 1594 to a lever 1595 pivoted on a fixed spindle 1597 and connected by a pin 1601 and slot 1602 to a lever 1603 pivoted on a fixed spindle 1605. The lever 1603 is connected by a pin 1609 and slot 1610 to a lever 1611 pivoted on a fixed spindle 1613 and connected by a pin 1617 and slot 1618 to a lever 1619 pivoted on a fixed spindle 1621. The lever 1619 is connected by a pin 1625 and slot 1626 to a lever 1627 pivoted on a fixed spindle 1629 and connected by a pin 1635 and slot 1636 to a lever 1637 pivoted on a fixed spindle 1639. The lever 1637 is connected by a pin 1645 and slot 1646 to a lever 1647 pivoted on a fixed spindle 1649 and connected by a pin 1653 and slot 1654 to a lever 1655 pivoted on a fixed spindle 1657. The lever 1655 is connected by a pin 1661 and slot 1662 to a lever 1663 pivoted on a fixed spindle 1665 and connected by a pin 1669 and slot 1670 to a lever 1671 pivoted on a fixed spindle 1673. The lever 1671 is connected by a pin 1677 and slot 1678 to a lever 1679 pivoted on a fixed spindle 1681 and connected by a pin 1685 and slot 1686 to a lever 1687 pivoted on a fixed spindle 1689. The lever 1687 is connected by a pin 1693 and slot 1694 to a lever 1695 pivoted on a fixed spindle 1697 and connected by a pin 1701 and slot 1702 to a lever 1703 pivoted on a fixed spindle 1705. The lever 1703 is connected by a pin 1709 and slot 1710 to a lever 1711 pivoted on a fixed spindle 1713 and connected by a pin 1717 and slot 1718 to a lever 1719 pivoted on a fixed spindle 1721. The lever 1719 is connected by a pin 1725 and slot 1726 to a lever 1727 pivoted on a fixed spindle 1729 and connected by a pin 1735 and slot 1736 to a lever 1737 pivoted on a fixed spindle 1739. The lever 1737 is connected by a pin 1745 and slot 1746 to a lever 1747 pivoted on a fixed spindle 1749 and connected by a pin 1753 and slot 1754 to a lever 1755 pivoted on a fixed spindle 1757. The lever 1755 is connected by a pin 1761 and slot 1762 to a lever 1763 pivoted on a fixed spindle 1765 and connected by a pin 1769 and slot 1770 to a lever 1771 pivoted on a fixed spindle 1773. The lever 1771 is connected by a pin 1777 and slot 1778 to a lever 1779 pivoted on a fixed spindle 1781 and connected by a pin 1785 and slot 1786 to a lever 1787 pivoted on a fixed spindle 1789. The lever 1787 is connected by a pin 1793 and slot 1794 to a lever 1795 pivoted on a fixed spindle 1797 and connected by a pin 1801 and slot 1802 to a lever 1803 pivoted on a fixed spindle 1805. The lever 1803 is connected by a pin 1809 and slot 1810 to a lever 1811 pivoted on a fixed spindle 1813 and connected by a pin 1817 and slot 1818 to a lever 1819 pivoted on a fixed spindle 1821. The lever 1819 is connected by a pin 1825 and slot 1826 to a lever 1827 pivoted on a fixed spindle 1829 and connected by a pin 1835 and slot 1836 to a lever 1837 pivoted on a fixed spindle 1839. The lever 1837 is connected by a pin 1845 and slot 1846 to a lever 1847 pivoted on a fixed spindle 1849 and connected by a pin 1853 and slot 1854 to a lever 1855 pivoted on a fixed spindle 1857. The lever 1855 is connected by a pin 1861 and slot 1862 to a lever 1863 piv

The rocking lever 173 is provided with a second notch 176 engaging flange 177 of sleeve 178 slidable on shaft 179 rotatable in walls 130 and 131 (FIG. 5). The sleeve 178 (FIG. 6) is angularly fast with shaft 179 and forms the driven part of a presetting clutch 181. The sleeve 178 is provided with a dog 182 adapted to engage with a notch 411 in cup 183 which forms the driving part of clutch 181. The cup 183 is fast with a gear 184 rotatable on shaft 179 and in mesh with gear 186 fixed on shaft 187 rotatable in plates 132 and 133 (FIG. 5).

Moreover on shaft 179 there is fixed a gear 188 in mesh with a gear 189 (FIGS. 1, 3 and 6). The gear 189 is fixed to an inclined shaft 191 (FIG. 2 and 3) which is adapted to rotate shaft 21 (FIG. 1), through a pair of gears 192 and 193, by one step for each half revolution of shaft 179.

The line-spacing control arrangement for independent platen 24 is similar to that for platen 23 and is disposed in the same housing 130, 134. It comprises a presetting electromagnet 196 (FIG. 11) which is normally deenergized and is adapted to be driven by the programmed device 145. The electromagnet 196 is connected mechanically to a corresponding presetting clutch 197, the dash lines in FIG. 11 representing mechanical connections and the continuous lines representing electrical connections. The clutch 197 (FIG. 5) is adapted to rotate shaft 198, receiving its motion from shaft 187 via a pair of gears 199, 201. The shaft 198 can rotate (FIG. 1) an inclined shaft 204 through a pair of gears 202, 203 and the inclined shaft 204 is adapted to rotate shaft 22, through another pair of helical gears 206 and 207, by one step for each half evolution of shaft 198.

The actuation of the line-spacing, both of platen 23 and of platen 24, is controlled by an actuating electromagnet 208 (FIG. 11) which is normally deenergized and is also adapted to be energized by programmed device 145. The electromagnet 208 (FIG. 7) comprises armature 209 pivoting on fixed spindle 140 and connected by a pin and slot 407 to slider 211. The armature 209 is normally held detached from electromagnet 208 by spring 212. The slider 211 is provided with a slot 213 in engagement with shaft 214 movable along a closed path in a similar manner to shaft 144 (FIG. 6). The slider 211 (FIG. 7) is moreover provided with lug 216 adapted to cooperate with one end of rod 217 which is pivoted at the other end to rocking lever 218 turning on spindle 164. The rod 217 is slidable vertically on fixed spindle 162 by means of notch 219.

The rocking lever 218 engages slider 221 slidable horizontally on spindle 167 and drawn to the left in FIG. 7 by spring 222. The slider 221 is connected to lever 223 which can turn on fixed spindle 224. The lever 223 is provided with an extension 226 against which there normally bears a tongue 227 of bail 228 turning on fixed spindle 229 and biased to pivot anticlockwise by spring 231. The bail 228 is moreover provided with tooth 232 which normally engages tooth 233 of clutch 234 and which, when engaged, connects gear 236 (FIG. 5) to shaft 237. The gear 236 is in mesh with gear 238 fixed on main shaft 239.

On the spindle 224 (FIG. 7) there is pivoted another bail 241 equipped with pin 242 engaged in a notch 412 of bail 228. The bail 241 is moreover provided with arm 243, adapted to cooperate with tooth 233 of clutch 234, and with arm 244 adapted to cooperate with cam 246 fixed on shaft 237. On the latter there is moreover keyed bevel pinion 247 (FIGS. 5 and 6) meshing with bevel pinion 248 keyed on shaft 187.

The push rod 217 (FIG. 7) has a step 251 against which there bears, by the action of spring 252, bar 253 of bail 254. The latter is pivoted on spindle 149 and is equipped with pin 256 against which there bears, by the action of spring 257, projection 258 of bail 259 pivoted on spindle 156. The bail 259 is moreover provided with arm 261 normally located out of the path of lug 154 of bail 148.

An extension 332 of lever 331 (FIG. 9) which can turn on spindle 224 can cooperate with tongue 227 of bail 228. The extension 332 is normally out of the path of tongue 227. The lever 331 is connected to slider 333 slidable on spindle 167. The slider 333 is drawn to the left by spring 336 and is en-

gaged with rocking lever 337 rotatable on spindle 164. The rocking lever 337 is connected by means of bar 338 to lever 339 pivoting on spindle 149. The lever 339 is adapted to cooperate with cam 342 fixed on shaft 146 of start clutch 147.

Let it be assumed first of all that the programmed operating device 145 (FIG. 11) of the accounting machine requires line spacing on main platen 23. The start electromagnet 157 is then deenergized temporarily and the presetting electromagnet 138 is energized in the manner which will be seen better hereinafter. Since the electromagnet 157 is deenergized, it permits slider 170 to move to the right in FIG. 7 and cause lever 155 to turn anticlockwise. The latter movement releases lug 154, as a result of which, due to the action of spring 160, bail 148 turns clockwise and releases tooth 151 of clutch 147, which is engaged and causes shaft 146 to begin a clockwise revolution. The arm 152 of bail 148 then bears against cam 153 on the shaft 146.

At the beginning of the cycle, cam 153 causes bail 148 to temporarily turn anticlockwise. Since, however, the start electromagnet 157 (FIG. 11) is still deenergized, lever 155 does not block lug 154 and bail 148 remains under the control of cam 153. During this cycle, shaft 146 produces the movement of shaft 144 (FIG. 6) and shaft 214 (FIG. 7) along a closed path. First of all, shaft 144 (FIG. 6) shifts to the left and, through the medium of slider 141, brings armature 139 into contact with electromagnet 138, the armature 139 remaining attracted by the latter. The lug 158 is thus brought below the end of push rod 159.

When shaft 144 thereafter begins to move upwards, lug 158 causes push rod 159 to move upwards and this causes rocking lever 163 to pivot clockwise. The rocking lever 163 shifts slider 166 forward and by means of lever 168 this slider 166 shifts slider 169 to the right. The latter causes rocking lever 173 to turn anticlockwise and, through the medium of flange 177, this rocking lever 173 causes sleeve 178 to slide on shaft 179 and engage clutch 181. In the event that the presetting electromagnet 138 is not energized, armature 139 does not remain attracted to it. The armature 139 and slider 14, are held back by spring 142 and thus the lug 158 is located below the end of push rod 161 during that portion of the closed path movement of shaft 144 which lifts lug 158 in an upward direction. It is to be noted that the lower portion of push rod 159 is closer to presetting electromagnet 138 than the lower portion of push rod 161 which thereby permits selective actuation of either of the push rods 159, 161 depending on whether the presetting electromagnet 138 is energized. During this first cycle, shaft 214 (FIG. 7) is also shifted, but its action has no effect since electromagnet 208 is still deenergized. The action of cam 342 (FIG. 9) of the main shaft 146 also has no effect on bail 228 (FIG. 7), because extension 332 (FIG. 9) is still out of the path of tongue 227.

Thereafter, shaft 146 causes switch 270 (FIG. 11) to close temporarily in a manner known conventionally and in a manner shown in the referenced application Ser. No. 773,872. The switch 270 sends a signal to the programmed device 145 which, as will be seen better hereinafter, effects the reenergization of start electromagnet 157 and the energization of the line-spacing actuating electromagnet 208. The electromagnet 157 now brings slider 170 back into the position shown in FIG. 7, but, since bail 148 is now turned clockwise by the action of cam 153, lever 155 is blocked by lug 154 and tensions spring 165. At the end of the cycle of shaft 146, arm 150 of bail 148 therefore does not disengage clutch 147, as a result of which shaft 146 begins a second cycle.

At the beginning of this second cycle, when cam 153 causes bail 148 to turn anticlockwise, lug 154 releases lever 155 which, due to the action of spring 165, jumps below lug 154, locking it in the position shown in FIG. 7. In this way, the disengagement of clutch 147 at the end of this second cycle is prearranged. During this second cycle, shaft 214 first moves towards electromagnet 208 and slider 211 then brings the armature 209 into contact with electromagnet 208, the armature 209 remaining attracted thereby. In turn, lug 216 of slider

211 is shifted below the end of push rod 217. In the event that electromagnet 208 is not energized, armature 209 does not remain attracted to it. The armature 209 and slider 211 are held back by spring 212 and thus the lug 216 is not located below the end of push rod 217 during that portion of the closed path movement of shaft 214 which lifts lug 216 in an upward direction. In this case as lug 216 is lifted, its movement will not contact the push rod 217 at all. Therefore, depending on whether electromagnet 208 is energized, push rod 217 may be selectively actuated by lug 216 during its closed path movement.

Simultaneously, cam 342 (FIG. 9) on shaft 146 causes lever 339 to turn clockwise and push bar 338 upwards. The latter then causes rocking lever 337 to pivot clockwise and push slider 333 to the right in the drawing.

The lever 331 then brings its extension 332 below tongue 227, where it remains until the end of the cycle of shaft 146.

Thereafter, when shaft 214 (FIG. 7) is shifted upwards, lug 216 shifts rod 217 upwards. The rod 217 then acts by means of its step 251 on bar 253, causing bail 254 to turn clockwise. The spring 257 therefore causes bail 259 to turn anticlockwise and bring its arm 261 under lug 154. The arm 261 thus prevents the initiation of another cycle of shaft 146 until rod 217 returns to the low position.

Moreover, as rod 217 moves upward, it causes rocking lever 218 to pivot clockwise and move slider 221 to the right. The latter causes lever 223 to turn anticlockwise and release tongue 227 of bail 228. The spring 231 is unable to make bail 228 turn anticlockwise, however, since tongue 227 is locked by lever 331 (FIG. 9). If, therefore, the presetting electromagnet 138 (FIG. 6) has been deenergized by chance during the second cycle of shaft 146, clutch 181 can be disengaged while the driving part of the kinematic chain is still stationary.

At the end of the second cycle of shaft 146, cam 342 (FIG. 9) allows spring 336 to release tongue 227 from extension 332, as a result of which spring 231 (FIG. 7) causes bail 228 to turn anticlockwise. The latter, in turn, causes bail 241 to turn clockwise and bring its arm 244 into contact with cam 246 and release tooth 233 from arm 243. This tooth 233 then causes clutch 234 to engage, so that shaft 237 begins to rotate clockwise. By means of bevel pinions 247 and 248 (FIG. 6), shaft 237 now sets shaft 187 in rotation and, therefore, also shaft 179, via clutch 181, which has been engaged before. Via the helical gears 188, 189, shaft 191 (FIG. 3) and gears 192 and 193 (FIG. 2), shaft 179 causes shaft 21 to rotate together with main platen 23 (FIG. 1).

Moreover, during the rotation of shaft 237 (FIG. 7), cam 246 acts on arm 244, causing bail 241 to turn anticlockwise and, therefore, bail 228 to turn clockwise. The arm 243 is therefore brought back into the path of tooth 233, so that after shaft 237 has rotated through 180° clutch 234 is disengaged. The tongue 227 of bail 228 is now locked in the high position by extension 226 of lever 223, which has been brought back into the position of FIG. 7 by spring 222 when shaft 214 has shifted downwards.

If the programmed device 145 (FIG. 11) now requires line spacing on independent platen 24 (FIG. 1), the electromagnets 157 and 208 (FIG. 11) are driven in a manner just the same as that described before, while presetting electromagnet 196 is energized in place of electromagnet 138. The start electromagnet 157 engages clutch 147 which, under the control of electromagnet 196, produces the engagement of clutch 197 presetting the line spacing of platen 24 by means of a kinematic chain similar to that of electromagnet 138 described with reference to FIG. 6.

As the electromagnet 138 is not now energized, armature 139 does not continue to be attracted by electromagnet 138 and lug 158 of slider 141 is disposed below push rod 161. When shaft 144 moves upwards, push rod 161, acting via rocking lever 163, slider 166, lever 168, slider 169 and rocking lever 173, reopens clutch 181 presetting the line spacing of platen 23. The actuating electromagnet 208 (FIG. 7), in turn, causes bails 228 and 241 to turn in opposite directions as

in the preceding case. The arm 243 thus releases tooth 233, thereby engaging clutch 234, which transmits (FIG. 5) the rotation to shaft 187 and, consequently, via clutch 197, to shaft 198 (FIG. 1), which causes shaft 22 to rotate together with independent platen 24. After shaft 237 (FIG. 7) has rotated through 180°, tooth 233 is again arrested by tooth 232.

Of course, line spacing of platen 24 can be operated simultaneously with that of platen 23 by energizing the two presetting electromagnets 138 and 196 (FIG. 11) simultaneously.

FEED OF THE CONTINUOUS FORMS

The continuous forms 69, 71 can advance step by step or in rapid-feed jumps. The step-by-step advance is effected by a line-spacing control arrangement for pin wheels 76, 83 which is similar to that for platens 23 and 24 and disposed in the same housing 130, 134 and is actuated by the same actuating electromagnet 208 (FIGS. 7 and 11).

The line-spacing control arrangement for continuous form 69 comprises a presetting electromagnet 272 (FIG. 11) which is normally deenergized and is adapted to be energized by programmed device 145. The electromagnet 272 is connected to a corresponding presetting clutch 273 (FIG. 5) by means of a

kinematic chain similar to that described with reference to FIG. 6 in the case of the line-spacing control arrangement for platen 23. The clutch 273 is adapted to transmit rotation of the shaft 187 to shaft 277 by means of a pair of helical gears 275 and 276. Through the medium of a pair of helical gears 278 and 279 (FIG. 3), the last-mentioned shaft 277 produces the rotation of an inclined shaft 281 which is adapted to rotate shaft 73 together with pin wheels 76, via another pair of helical gears 282 and 283, by one step for each revolution of shaft 277 (FIGS. 1 and 2).

The line-spacing control arrangement for the continuous form 71 comprises a presetting electromagnet 284 (FIG. 11) which is normally deenergized and is adapted to be energized by programmed device 145. The electromagnet 284 is connected to a corresponding presetting clutch 286 (FIG. 5) by means of a kinematic chain similar to that of electromagnet 272 and to that described with reference to FIG. 6. The clutch 286 is adapted to transmit rotation of shaft 187 to shaft 289 by means of a pair of helical gears 287, 288. Through the medium of a pair of helical gears 291, 292 (FIG. 3), the last-mentioned shaft 289 rotates an inclined shaft 293 which is adapted to rotate shaft 81 together with pin wheels 83, via another pair of helical gears 294, 296, by one step for each half revolution of shaft 289.

The feed of the continuous forms 69, 71 in jumps is preset (FIG. 11) by the same electromagnets 272 and 284 that pre-range the line spacing. The actuation, on the other hand, is controlled by another actuating electromagnet 297 which is normally deenergized, this electromagnet 297 comprising (FIG. 8) an armature 298 pivoting on spindle 140 and engaged by means of a notch 413 over pin 299 fixed to slider 301, the armature 298 being normally held detached from electromagnet 297 by spring 302. The slider 301 is supported by shaft 214 by means of slot 303. Pivoted on pin 299 is slider 304 connected by means of spring 306 and a pin 409 and slot 408 connection to lever 308 which can turn on fixed spindle 309. The lever 308 is moreover connected to one end of bar 311. The other end of bar 311 is connected to rocking lever 312 pivoting on spindle 164. The rocking lever 312 is provided with tooth 310 adapted to cooperate with tooth 313 of bail 314 pivoted on fixed spindle 167.

The bail 314 is moreover provided with lug 315 adapted to cooperate with shoulder 316 of slider 221 controlling the production of the line spacing. The bail 314 is also provided with arm 320 carrying pin 317 engaged slot 321 in slider 323. The latter is moreover connected to arm 320 by means of spring 322 and is drawn to the right in FIG. 8 by spring 324. The slider 323 is pivoted to lever 325 pivoted on fixed spindle 229 and adapted to cooperate with cam 326 fixed on shaft 237 of actuating clutch 234 for the line spacing (FIG. 7).

The feed jump of each perforated form 69 and 71 is controlled by corresponding photoelectric devices 327 and 328 (FIG. 11). These photoelectric devices 327 and 328 are conventionally known and are described only briefly here. Each photoelectric device 327, 328 comprises an endless tape 415 having a length corresponding to the single form 69, 71 and adapted to advance synchronously with the corresponding forms 69 and 71, respectively. The tape 415 is perforated along five tracks 416. In each track 416 the holes 417 represent the successive vertical positions in which a form 69, 71 is to stop. The track 416 to be read is selected in known manner by programmed device 145 of the accounting machine.

In order to drive device 327 it is connected by means of gear 381 (FIG. 5) to shaft 382 rotatable in plates 132, 133 of housing 130, 134. The shaft 382 is connected by means of a worm wheel 383 and a worm 384 to shaft 277 of clutch 273 for pin wheels 76 which carry form 69 along. Similarly device 328 (FIG. 11) is connected by means of gear 386 (FIG. 5) to shaft 387 rotatable in the same plates 132, 133. The shaft 387 is connected by means of a worm wheel 338 and a worm 389 to shaft 289 of clutch 286 for pin wheels 83 which carry form 71 along.

When the programmed device 145 (FIG. 11) of the machine requires a feed jump, it energizes start electromagnet 157 and presetting electromagnet 272 or 284 in the manner which will be described hereinafter. Moreover, device 145 energizes both line-spacing actuating electromagnet 208 and jump actuating electromagnet 297. Finally, the programmed device 145 selects in the photoelectric device 327 or 328 corresponding to the energized presetting electromagnet 272 or 284 that track 416 of the perforated tape 415 which is to be read to control the jump to be effected. As already seen, owing to the actuation of the line spacing, slider 221 is shifted to the right in FIG. 8. The slider 221 then deprives lug 315 of the support of shoulder 316.

During the 180° rotation of shaft 237, shaft 73 (FIG. 2) or shaft 81 is now rotated, according to whether electromagnet 272 (FIG. 11) or electromagnet 284 has been energized. When cam 326 (FIG. 8) on shaft 237 causes lever 325 to turn clockwise, the lever 325 causes the return of slider 323 to the left. The bail 314, however, remains locked by tooth 310 of rocking lever 312, thus tensioning spring 322. The slider 221 therefore cannot be brought back to the left to produce the disengagement of clutch 234 (FIG. 7) and shaft 237 continues to rotate, producing a series of line-spacing operations on the continuous form 69, 71 selected.

When photoelectric device 327 or 328 (FIG. 11) reads a hole 417 on the selected track, the hole indicating the end of the feed jump, it generates a signal which is transmitted to programmed device 145. In response, programmed device 145 causes electromagnet 297 (FIG. 8) to be deenergized, as a result of which spring 302 causes armature 298 to be moved away and lever 308, together with bar 311 and rocking lever 312, to return to the position of FIG. 8. The tooth 310 thus releases tooth 313 of bail 314 which, under the control of shaft 237, now releases step 316 of slider 221 from lug 315. The slider 221 is now brought back to the inoperative position by spring 222, so that at the end of the cycle of shaft 237, lever 223 (FIG. 7) locks bail 228 in the position shown in the drawing, disengaging clutch 234.

Of course, the line-spacing movement can be effected simultaneously in the two continuous forms 69 and 71 (FIG. 1) and simultaneously with the line spacing on platens 23 and 24. In addition, the feed jump can be effected simultaneously in the two continuous forms 69 and 71. In this case, however, the programmed device 145 (FIG. 11) selects the track 416 to be read only on one of the two photoelectric devices 327, 328, as a result of which the two forms 69 and 71 will perform equal jumps. If the two forms 69 and 71 require jumps of different lengths, the programmed device 145 can be prearranged in such manner as to command, after the common jump, a second jump for that form 69 or 71 requiring a jump of greater length.

Finally, if, on command of the feed of the continuous forms 69 and 71 (FIG. 2), shaft 103 is holding paper-pressing rollers 101 against platens 23 and 24, the programmed operating device 145 (FIG. 11), simultaneously with the energization of electromagnets 272 and 284, commands rotation of shaft 103 (FIG. 2) in such manner as to release forms 69 and 71 themselves. The spring 324 (FIG. 8) then causes slider 323 to move to the right and the slider 323 causes bail 314 to turn clockwise and couple shoulder 316 with lug 315 in such manner as to prevent the return of slider 221 to the left. Moreover, slider 323 causes lever 325 to turn anticlockwise, bringing it into contact with cam 326.

This coupling action occurs on the command of any line-spacing operation. However, during the cycle of shaft 237, cam 326 normally causes lever 325 to turn clockwise and, via slider 323, cause bail 314 to turn anticlockwise and release slider 221, which is thus brought back to the inoperative position, to the left in FIG. 8, by spring 222.

In the case of command of a feed jump of the continuous forms 69 and 71, since electromagnet 297 is energized together with electromagnet 208 (FIG. 11), in the second cycle of main shaft 146 (FIG. 7), armature 298 (FIG. 8) is brought into contact with electromagnet 297 by shaft 214, as a result of which pin 299 is also moved to the left together with slider 304. By means of spring 306, the latter causes lever 308 to turn clockwise and the lever 308 pushes bar 311 upwards. The rocking lever 312 is thus rotated anticlockwise so as to bring tooth 310 below tooth 313 of bail 314, so that the latter remains locked in the coupled position of slider 221.

FEED CONTROL

The various controls effected by the programmed operating device 145 (FIG. 11) for producing the various paper feed operations will now be described in detail. To this end, the programmed operating device 145 comprises an electronic unit 340 adapted to read from time to time the program information recorded on a magnetic tape in the form of separate characters for each operation to be effected, and to transmit the relative signals to a series of control circuits. More particularly, for control of the feed movements of the paper, between the electronic unit 340 and the four presetting electromagnets 138, 196, 272 and 284 there are provided four corresponding flip-flops RP, RS, SI and SS. The unit 340 is adapted to switch each of these flip-flops RP, RS, SI and SS to a first operative state to energize the corresponding electromagnet 138, 196, 272, or 284, on reading of the corresponding character on the magnetic tape. In the absence of such character, unit 340 brings the corresponding flip-flop RP, RS, SI and SS back into the other state, in which the respective electromagnet 138, 196, 272, or 284 is deenergized.

The unit 340 is adapted to drive the start electromagnet 157 by means of a START flip-flop normally in the operative state to energize start electromagnet 208. On the reading of the corresponding character, unit 340 sends a signal to a coincidence or AND circuit 391. On the closing of switch 270, the coincidence circuit 391 then transmits a signal which changes the flip-flop INT over to the operative state to energize electromagnet 208. The flip-flop INT is then changed over to the inoperative state on the closing of switch 356, which is normally open and is adapted to be actuated by means of arm 353 (FIG. 10) of bail 351 pivoted on fixed spindle 352. A second arm 350 of bail 351 is connected by means of connecting rod 349 to another bail 347 pivoted on a fixed spindle 348 and normally bearing by the action of spring 344 and arm 346 on the cam 343 of actuating shaft 237.

A second switch 362 is adapted to be actuated by lever 359 rotatable on spindle 352 and normally bearing by the action of spring 358 against an eccentric 357 mounted on shaft 103 (FIG. 2) controlling the front paper-pressing rollers 101. The switch 362 (FIG. 11) is connected electrically to the electronic unit 340 to signal the position of rollers 101 (FIG. 2) continuously to unit 340 so as to permit simultaneously with

the energization of the presetting electromagnets 272 and 284, the rearrangement of the rotation of shaft 103 if the rollers 101 are in the open position.

The electromagnet 297 (FIG. 11) is driven by unit 340 by means of flip-flop SAL, normally in the inoperative state, to energize electromagnet 297. On the reading of the corresponding character, unit 340 transmits a signal to a coincidence or AND circuit 392. On the closing of switch 270, the coincidence circuit 392 then sends a signal which changes flip-flop SAL over into the operative state to energize the electromagnet 297.

The flip-flop SAL is then changed over into the inoperative state when one of the photoelectric devices 327 and 328 reads the end-of-feed-jump position on the track 416 of the perforated tape 415 selected by unit 340.

Since contact 270 is closed by shaft 146 (FIG. 7) after shaft 214 has moved upwards, flip-flops INT and SAL (FIG. 11) remain in the inoperative state and the electromagnets 208 and 297 remain deenergized during the first part of the first cycle of shaft 146. The flip-flops INT and SAL thus energize actuating electromagnets 208 and 297 with a delay with respect to the presetting electromagnets 138, 196, 272 and 284, as a result of which the relevant command is effected only in the second cycle of shaft 146.

We claim:

1. In a paper feed system for an accounting or like machine including a cylindrical platen for supporting a journal sheet, a line feed mechanism operable to rotate the platen for line feeding said journal sheet, a form feed mechanism operable for feeding a continuous form around the platen independently from said journal sheet and superimposed thereto, a first feed shaft rotatable for operating said line feed mechanism, a second feed shaft parallel to said first feed shaft and rotatable for operating said form feed mechanism, a continuously rotatable motor shaft, and programmed operating means, the improvement comprising:

a normally disengaged first presetting clutch engageable for causing said first feed shaft to be rotated, a normally disengaged second presetting clutch engageable for causing said second feed shaft to be rotated, a driving member included in each one of said presetting clutches and rotatably mounted on the corresponding one of said first and second feed shafts, a driven member included in each one of said presetting clutches and rotatable bodily with said corresponding feed shaft, each of said driven members being engageable with the corresponding driving member only when said corresponding driving member is stationary, a common shaft located perpendicular to said first and second feed shafts and drivingly connected to said driving members for concomitant rotation, a normally disengaged actuating clutch engageable for causing said common shaft to be rotated by said motor shaft, and engaging means controlled by said programmed operating means to cause the engagement of said actuating clutch and selectively of said first and second presetting clutches.

2. A paper feed system as recited in claim 1, wherein each of said driven members is formed of a sleeve axially slidable but angularly secured to the corresponding feed shaft, said sleeve being provided with a projection engageable with a notch provided in the corresponding driving member.

3. A paper feed system as recited in claim 1, comprising a cyclic actuating mechanism operable under the control of the programmed operating means, said engaging means comprising for each of the actuating and first and second presetting clutches an electromagnet, an armature and an element connected to said armature and actuated by said cyclic actuating mechanism upon energization of the corresponding electromagnet for causing the engagement of the corresponding clutch.

4. A paper feed system as recited in claim 3 wherein the cyclic actuating mechanism comprises a start clutch and further engaging means for engaging said start clutch under

the control of the programmed operating means simultaneously with energization of the electromagnets corresponding to the first and second presetting clutches.

5. A paper feed system as recited in claim 4 further comprising: causing means for causing the start clutch to effect two consecutive cycles, the element relative to the selected presetting clutch being actuated by said cyclic actuating mechanism during a first cycle of said start clutch, and

control means actuated by the cyclic actuating mechanism to delay the action of the programmed operating means on the electromagnet of the actuating clutch to cause the corresponding element to be actuated during the second cycle of the start clutch.

6. A paper feed system as recited in claim 5 wherein the actuating clutch is of the one-cycle type,

said programmed operating means including means to selectively energize another electromagnet to prevent disengagement of the actuating clutch at the end of the cycle so that the feed commanded constitutes a jump consisting of a plurality of line-spacing steps.

7. A paper feed system as recited in claim 6 further comprising:

means to deenergize the said another electromagnet by a signal derived when the required paper jump has been effected.

8. A paper feed system as recited in claim 5 wherein the start clutch is normally held disengaged by a release element releaseable by a start electromagnet when said start electromagnet is deenergized by the programmed operating means,

said causing means comprising a switch operable to be closed to energize the start electromagnet, the cyclic actuating mechanism being operative first to engage the release element and then to close said switch, as a result of which this engagement remains without any effect in the first cycle of the cyclic actuating mechanism.

9. A paper feed system as recited in claim 8 wherein said start electromagnet is energized by a bistable circuit brought into an inoperative state by the programmed operating means and restored to the operative state when the switch is closed.

10. A paper feed system as recited in claim 8 wherein the electromagnet of the actuating clutch is energized by a bistable circuit brought into an operative state by the programmed operating means and restored to the inoperative state on the closing of said switch effected during the cycle of the actuating clutch.

11. A paper feed system as recited in claim 7 wherein said means to selectively energize another electromagnet includes a bistable circuit brought into an operating state by the programmed operating means and said means to deenergize another electromagnet includes a photo-electric tape reader which senses a tape associated with each one of said presetting clutches and moved by the associated presetting clutch when engaged.

12. A paper feed system as recited in claim 1 wherein said cylindrical platen includes a main platen for supporting the journal sheet and the continuous form and an independent platen for supporting a second continuous form, a second form feed mechanism for advancing the second continuous form over said independent platen, said second form feed mechanism being advanced by a third feed shaft, said third feed shaft being provided with a normally disengaged third presetting clutch including a third driving member rotated by said common shaft on the engagement of the actuating clutch, and wherein the driven member of each of said presetting clutches comprises a sleeve axially slidable on the corresponding feed shaft and engageable with the respective driving member by axial movement thereof.

13. A paper feed system as recited in claim 12 wherein said actuating clutch is of the type having a 180° cycle and comprises a clutch tooth arrested alternately by two stop elements interconnected in such a manner as to be brought simultaneously out of the path of the clutch tooth or brought back simultaneously into this path.

UNITED STATES PATENT OFFICE
CERTIFICATE OF CORRECTION

Patent No. 3,653,483 Dated April 4, 1972

Inventor(s) Alessandro Cortona, et. al.

It is certified that error appears in the above-identified patent and that said Letters Patent are hereby corrected as shown below:

Column 2, line 2, cancel "auxiliary" ; lines 10-11, cancel "as described in copending application Ser. No. 774,375 Nov. 8, 1968" . Column 6, line 39, "41" should read -- 141 -- . Column 9, line 3, "11)" should be canceled; line 21, "338" should read -- 388 -- ; line 50, after "track" insert -- 416 -- and after "hole" insert -- 417 -- . Column 10, line 55, after "electromagnet", insert -- 157. Following the reading of the corresponding character, unit 340 causes the START flip-flop to change over to the inoperative state, as a result of which it causes start electromagnet 157 to be deenergized. The START flip-flop is then brought back to the operative state owing to the closing of switch 270 effected by main shaft 146 (Fig. 7).

The unit 340 (Fig. 11) drives the line-spacing actuating electromagnet 208 by means of a flip-flop INT, normally in the operative state, to energize electromagnet -- .

Signed and sealed this 19th day of December 1972.
